KNITTING MACHINE

George Wilders, Kegworth, and John Edward Lynam, Mapperley, England, assignors to William Cotton Limited, Loughborough, England

Application May 29, 1942, Serial No. 445,043
In Great Britain April 19, 1941

19 Claims. (Cl. 66—82)

This invention is for improvements in and relating to knitting machines, and is particularly but not exclusively concerned with Cotton's Patent or other straight bar knitting machines. In such machines it is necessary to effect a temporary reduction of speed during those courses in which fashioning or other transfer operations, such for example as clocking, are effected; for convenience in the ensuing description reference is only made to fashioning and to the fashioning course, but it is to be understood that these expressions are employed in a broad sense to include all transfer operations and the courses wherein they occur. If the necessary speed reduction is to be effected without delaying the knitting operations, it must need be effected automatically and exceedingly rapidly, and it is an object of the present invention to provide means for effecting such speed variation. It is a further object of the invention to provide means for effecting speed variation both manually and automatically. A still further object of the invention is to provide apparatus for automatically effecting a plurality of speed variations and, as hereinafter appears, in its preferred form the apparatus according to this invention makes provision for the following: (1) an infinitely variable speed control by hand; (2) an automatic reduction in speed for one course for fashioning and a return to the speed originally obtaining; (3) an automatic speed reduction for a given number of courses and a return to the speed originally prevailing, which reduction may be for the purposes of plating and which reduced speed is preferably the same as the fashioning speed; (4) an automatic reduction to a particularly low speed (necessary to permit of automatic movements, such for example as welt turning and carrier changing) and a return to the original high speed; (5) an automatic stoppage of the driving motor or an interruption of the drive at a predetermined point in time, as for example at the completion of a stocking blank.

As viewed from one aspect this invention provides in or for a knitting machine, particularly a Cotton's patent or other straight bar knitting machine, speed regulating apparatus comprising a speed controlling member movable to effect progressive speed variation, a manual control for moving said member to procure the desired speed (e. g., for normal working) and automatic control means for moving said member without interference with the manual control to effect (a) speed reduction for one course, (b) speed reduction for a predetermined plurality of courses,

and (c) reduction to a speed lower than either (a) or (b), and, after each reduction, a return to the speed set by the manual control. The invention further includes in or for a knitting machine, particularly a Cotton's patent or other straight bar knitting machine, speed regulating apparatus comprising a speed varying device, a manual control for controlling it to determine or set the speed, and automatic control means for controlling it to give at least two different temporary speed reductions from the speed set by the manual control. By the expression "manual control" there is to be understood a control adapted to be operated by the attendant, and the expression is not strictly limited to a control adapted for operation by hand. By the expression "automatic control means" there is meant control means which is adapted to be operated automatically from the machine itself at the appropriate times, for example by means of a chain or other patterning device.

The automatic control means is preferably constructed as a unit capable of assembly separate from the main part of the machine and of attachment in unit form to said machine, the manual control being thereupon connected to a suitable operating member, such for example as the power rod in the case of a Cotton's patent machine, and the automatic control means being connected to the chain or other device whereby its operations are timed.

The invention is particularly but not exclusively applicable to a machine which is driven by an alternating current variable-speed shunt motor having either the brush gear movable to effect speed variation or having a fixed brush gear and a separate induction regulator by rotation of which the speed of the motor is controlled. Alternatively a variable speed gear may be interposed between the motor and the working parts of the machine to effect the necessary speed variation.

The foregoing and other features of the invention set out in the appended claims are incorporated in the construction which will now be described, as an example, with reference to the accompanying drawings, in which

Figures 1 and 2 together constitute a rear elevation of the apparatus;

Figures 3 and 4 together constitute an end elevation thereof, partly in section;

Figure 5 is a rear elevation of a portion thereof, on a larger scale and partly in section;

Figure 6 is a plan of the mechanism shown in Fig. 5;

Figure 7 is a rear elevation of a further portion thereof, on said larger scale, while

Figure 8 is a plan of the mechanism shown in Fig. 7.

In the illustrated construction according to this invention applicable to Cotton's patent or other straight bar knitting machine, an alternating current variable speed motor 10, Figs. 1 and 3, having a variable brush commutator (the speed varying device aforesaid) is employed, which commutator is rotated by means of a pinion 11 driven by a quadrant 12 biased in a speed-increasing direction (i. e., a clockwise direction as viewed in Fig. 3, the biasing means (not shown, but desirably a spring) preferably acting on pinion 11. This quadrant 12 constitutes the speed-controlling member aforesaid. The toothed part of the quadrant is located above its pivot 12a, and below its pivot the quadrant 12 is provided with an arm 13 to which there is pivoted at 14a a sleeve 14 slidably transfixed by a push-and-pull rod 15 which is connected to a lever 16 fixed on a rocking control shaft 17 of the automatic control unit, said lever 16 being itself connected by suitable mechanism 18—23 to the power rod 24 of the machine. It is by way of this push-and-pull rod 15 that the speed of the machine is set manually (by adjustment of the power rod). The sleeve 14 is accommodated on the push-and-pull rod 15 and located by an adjustable stop or collar 25 on the rod 15 and is biased by the aforesaid biasing means into contact with the stop. It will therefore be apparent that movement of the quadrant 12 in the speed-increasing direction can only be effected when accompanied or caused by movement of the power rod 24, but that, whatever the setting of the power rod 24, movement of the quadrant 12 in a speed-reducing direction can be effected without further movement of said power rod 24.

The quadrant is also movable automatically from the automatic control unit. Above its pivot 12a the quadrant 12 has another sleeve 26 pivoted to it at 26a which second sleeve 26 slidably embraces a longer sleeve 27 which in turn slidably embraces a second push-and-pull rod 28 between an adjustable stop 29 and a slidable collar 30 that is urged against the end of sleeve 27 by a compression spring 33 encircling the rod between slidable collar 30 and another adjustable stop 34. This second rod 28 is pivoted to the upper end of a speed-control lever 31 mounted on and secured to a shaft 32 parallel to the aforesaid rock shaft 17. The compression spring 33 urges the sleeve 27, in the speed-reducing direction, up to the adjustable stop 29 on the said rod 28 and acts as a shock absorber. It is by way of this second push-and-pull rod 28 that all automatic adjustments in speed are effected.

Above the second shaft 32 there is journaled a short auxiliary cam shaft 35 which is driven from the main cam shaft 135 at equal speed thereto. This auxiliary cam shaft 35 carries two oppositely disposed worms or threads 36, 37, best shown in Fig. 5, each conveniently of a single turn. Between the said worms 36, 37 there is a cam 38 which may be termed an automatic stop switch timing cam, and at the end of the auxiliary shaft 35 there is a cam 39 which may be termed a fashioning cam. Above the auxiliary cam shaft 35 a block 40 is slidably supported on guides 41 for movement lengthwise of the axis of the shaft 35. This block 40 carries two plungers 42, 43, one for engagement with either worm 36, 37, which plungers 42, 43 are connected

by a lever 44, 46, pivoted at 45 and positioned by spring loaded plunger 75 so that when one plunger is lowered into engagement with one worm the other is raised from engagement with the other worm and vice versa. These plungers 42, 43 are controlled through a suitable control rod 47 and other mechanism 48 (see Fig. 7) from the chain of the machine, it being seen that the rod 47 is biased to the right by return spring 73 and carries two spaced tappet members 48 between which an end of lever 46 is located. The sliding block 49 is connected by a link 49 to a bell-crank-lever 50 having a tappet end which bears against the upper end of the speed-control lever 31 aforesaid. Therefore when one plunger is engaged with a worm and the block traverses in one direction (to the left in Figs. 2, 5 and 6 and downwards into the plane of the paper as viewed in Fig. 4), the speed-control lever 31 is moved in a speed-reducing direction, and when the other plunger is engaged with the other worm and the block traverses in the reverse direction the speed-control lever 31 is permitted to return in the speed-increasing direction so that the speed is restored to that determined by the manual control. When a plunger reaches either end of its worm, it remains in situ until the other plunger is engaged with the other worm to effect the return of the block. Therefore when the speed has been reduced, the reduced speed may be maintained for any desired number of revolutions of the main cam shaft 135 as determined by the set-out of the chain. The foregoing portion of the apparatus is employed to afford an automatic speed decrease to a particularly low speed in order to permit automatic movements such for example as welt turning and carrier changing to take place. The use of worms for effecting this speed decrease and its subsequent increase permits the speed variation to be effected very gradually, each throughout a single course and a complete revolution of the main cam shaft (if each worm consists of a single turn), so that shock to the power transmission of the machine is minimised.

The automatic reduction in speed for a single course for fashioning is effected by the fashioning cam 39 which co-operates with a truck 51 on the speed-control lever 31 aforesaid, which truck is capable of being shogged into and out of engagement with the cam by means of a fork 52, Figs. 3, 7 and 8, on an auxiliary rod 53 coupled to a second control rod 54. It will be seen from Figs. 7 and 8 that rod 54 has fixed to it a member 59 having two spaced fork arms 59' that are slidably transfixed by the truck-shogging rod 53; a compression spring 70 encircles said rod 53 between the left hand one of the two fork arms 59' and a collar 71 adjustably fixed to rod 53, whereby said collar 71 is urged against the right-hand fork arm. The truck 51 is therefore moved positively, to the left Figs. 7 and 8, into register with cam 39 but is moved in the opposite direction through spring 70. Attention is also directed to return spring 72 extending between right-hand arm 59' and a part of the frame of the apparatus. The second control rod 54 is under the control of two separate patterning or selective mechanisms, one to effect the speed reduction for a single course for fashioning, and the other to effect an automatic speed reduction for a predetermined number of courses for plating, the plating speed being the same as the fashioning speed and both being higher than the welt-turning or carrier-changing speed (it being under-

stood that cam 39 is adapted to displace lever 31 to a less extent than does the worm-operated sliding block 40 and lever 50. The first patterning mechanism may be the chain of the machine. In order to provide for the speed reduction for a predetermined plurality of courses for plating or for one or more courses of fashioning, a catch 55 is provided which, after the speed-control lever 31 has been rocked by the fashioning cam 39 to effect the speed reduction, engages a short arm 56 on shaft 32 and prevents the return of said lever 31 until such time as said catch 55 is released. The said catch 55 is applied, by the second control rod 54, through a tension spring 51 extending between an end of the said catch and a part of member 59 on rod 54 but is released positively only after the truck 51 has reached the highest point of the cam 39. The arrangement is such that movement of the second control rod 54 to the left (Figs. 7 and 8) to shog the truck 51 into register with the fashioning cam 39 loads the spring 51, so that when the speed-control lever 31 is displaced by the cam 39 the catch 55 springs into its engaged position. This movement brings an abutment 55a associated with the catch 55 into contact with a stop-face 59a of member 59 so that when the rod 54 is moved in the reverse direction (to remove the truck 51 from register with the cam 39) the catch 55 is released as just described.

The plating and fashioning speeds are not necessarily the same. Two cams may be provided, giving different speeds for fashioning and for plating, and the truck may be shogged into register with either of them.

The automatic stop switch timing cam 38 (Figs. 4 and 5) co-operates with a cam lever 58, Figs. 4, 5 and 7, freely mounted on the rock shaft 32 and connected by an adjustable push rod 59b, Figs. 2, 3 and 8, to a rocking finger 60 which is freely mounted on the rock shaft 17 and co-operates with a stop switch roller 61 capable of depression to close the contacts of an automatic stop switch 81. There is a catch 62, Figs. 7 and 8, which is pivoted on a fixed part of the frame of the apparatus and co-operates with an adjustable tappet in an arm 58' of cam lever 58 normally to prevent the said cam lever from making contact with the automatic stop switch timing cam 38, but which is tripped or released at the appropriate times by the first said control rod 47 and a catch lever 63 pivoted to a member 74 secured to said rod. The stop switch roller 61 is biased in the contact-breaking direction and therefore as soon as the catch or trip 62 is released the cam lever 58 makes contact with the aforesaid timing cam 38 and, at an appropriate stage in the rotation of the latter, will descend a flank of said cam and the switch will break. The first control rod 47 moves in two steps. The first step operates the plungers 42, 43; the second trips the aforesaid catch 62.

The automatic stop switch is useful in stopping the machine automatically after the completion of a series of operations, as for example after the completion of an article such as a stocking blank.

This automatic switch is re-set by means of the power rod 24. To this end on the rock shaft 17 there is a re-setting finger 64 which, upon the final movement of the said rock shaft in the off direction, displaces the rocking finger 60 (by means of tappet 64') and the said switch roller 61 so that the stop switch contacts are

closed. Additionally this movement serves to replace the trip or catch 62 in a position in which it holds the cam lever 58 out of engagement with the timing cam 38. To this end, 5 finger 64 shogs a short rod 65 guided in a lug on finger 60 and having a collar 66 thereon, which collar rocks catch lever 63 out of engagement with catch 62.

There is also a manually operable stop switch 10 82 which for convenience is referred to as the main switch. This main switch has a switch-operating roller 67 which is oppositely arranged to the stop switch roller. That is to say it is 15 spring biased to move in the same direction as said stop switch roller but, upon such movement, to cause the switch to make contact. This main switch roller is engaged by a finger 68 fixed on the rock shaft 17 and is therefore controlled by the power rod.

From the foregoing description it will be appreciated that when the power rod 24 is in one of its extreme positions the main stop switch is broken. Initial movement from this extreme position rotates the rock shaft 17 and (operating through finger 68) causes the main switch 82 to close so that the machine starts up at its lowest speed. Further rotation of the rock shaft 17 permits the quadrant 12 to rotate in a speed-increasing direction so that the machine speeds up. This movement of the quadrant is of course effected under the bias applied to the pinion 11 and its extent is determined by the extent to which the power rod is moved manually; the sleeve 14 remains in contact with stops 25, so that subsequent movement of the power rod in the reverse direction would result in movement of the quadrant 12 in the speed decreasing direction, but the sleeve 26 moves along sleeve 27 as far as the buffer stop 30 so as to permit subsequent automatic speed-reducing movements of the quadrant to be effected by the automatic control unit operating through rod 28. On movement of the power rod in reverse direction towards the aforesaid extreme position the quadrant is rotated through rod 15 and the machine is slowed down and eventually, upon reaching said extreme position, the main switch is broken so that the machine is stopped.

It will be seen that the automatic control mechanism, other than certain of the connections between rock shaft 17 and the power rod 24 and connections for operating the control rods 47 and 54 from the main and other patterning mechanism, is constructed as a complete unit or sub-assembly capable of being attached as such to the knitting machine and of being connected by rods 15 and 28 to the speed-controlling member (i. e., quadrant 12) of the speed varying device. The frame of the said unit comprises connected brackets 76, arranged to be bolted or otherwise attached to a suitable part of the machine frame such as the member indicated at 11 and supporting interconnected side frame members 78. This frame affords support for the stop switch 81 and main switch 82, and for a fuse or switch box or the like 83.

We claim:

1. Knitting machine speed-regulating apparatus, particularly suitable for Cotton's patent or other straight bar machines, comprising a speed-controlling member movable to effect progressive speed variation, a manual control for moving said member to procure the desired speed, and automatic control means for moving said member without interference with the manual control

to effect (a) speed reduction for one course, (b) speed reduction for a predetermined plurality of courses, and (c) reduction to a speed lower than either (a) or (b), and, after each reduction, a return to the speed set by the manual control, wherein the automatic control means is adapted to effect a gradual reduction from and gradual return to the speed set by the manual control, and comprises a worm-driven member movable to and fro to effect said gradual reduction and increase; a pair of simultaneously rotatable worms for coupling alternatively to the worm-driven member to drive it in one direction or the other according to which worm is coupled to it; and coupling means controllable by a patterning device for effecting said alternative coupling.

2. Knitting machine speed-regulating apparatus, comprising a speed varying device, a manual control for controlling it to determine or set the speed, and automatic control means for controlling it to give at least two different temporary speed reductions from the speed set by the manual control, wherein the automatic control means comprises a member movable in one direction to effect a speed reduction from that set by the manual control and in the reverse direction to restore the speed to that set; a rotatable cam for displacing said member through a predetermined amplitude to effect a speed reduction and restoration; a worm-driven member movable to and fro to displace the first said member independently of the cam; two worms rotatable simultaneously with the cam for alternative coupling to the worm-driving member to shift it in one direction or the other according to which worm it is coupled to: one worm for shifting the worm-driven member in one direction to effect and maintain a greater speed-reducing displacement of the first said member than is producible by the cam, and another worm for shifting the worm-driven member in the other direction to result in speed restoring movement of the first said member; and coupling means controllable by a patterning device for effecting said alternative coupling.

3. Knitting machine speed-regulating apparatus, comprising a speed varying device, a manual control for controlling it to determine or set the speed, and automatic control means for controlling it to give at least two different temporary speed reductions from the speed set by the manual control, wherein the automatic control means comprises a member movable in one direction to effect a speed reduction from that set by the manual control and in the reverse direction to restore the speed to that set; a rotatable cam for displacing said member through a predetermined amplitude to effect a speed reduction and restoration; a worm-driven member movable to and fro to displace the first said member independently of the cam; two worms rotatable simultaneously with the cam for alternative coupling to the worm-driven member to shift it in one direction or the other according to which worm it is coupled to: one worm for shifting the worm-driven member in one direction to effect and maintain a greater speed-reducing displacement of the first said member than is producible by the cam, and another worm for shifting the worm-driven member in the other direction to result in speed restoring movement of the first said member; and coupling means controllable by a patterning device for effecting said alternative coupling, combined with a cam follower for the cam-operated member, and means controllable

by a patterning device for effecting a relative shogging between said follower and cam to bring them into and out of co-operating register.

4. Knitting machine speed-regulating apparatus, comprising a member movable in one direction to effect a speed reduction and in the reverse direction to restore the speed, a rotatable cam for displacing said member through a predetermined amplitude to effect said speed reduction and restoration, a catch for holding the said member in its displaced and speed-reducing attitude, means controllable by a patterning device for determining the operation of said catch, a worm-driven member movable to and fro to displace the first said member independently of the cam, two worms rotatable simultaneously with the cam for alternative coupling to the worm-driven member to shift it in one direction or the other according to which worm it is coupled to: one worm for shifting the worm-driven member in one direction to effect and maintain a greater speed-reducing displacement of the first said member than is producible by the cam, and another worm for shifting the worm-driven member in the other direction to result in speed restoring movement of the first said member; and coupling means controllable by a patterning device for effecting said alternative coupling.

5. In a knitting machine, speed-regulating apparatus comprising in combination: a manually-operable stop device and an automatically-operable stop device for stopping the machine; means controllable by a patterning device for determining the operation of the automatically-operable stop device; a speed controlling member movable to effect progressive speed variation; a manual control for moving said member to procure the desired speed; and automatic control means for moving said member without interference with the manual control to effect (a) speed reduction for one course, (b) speed reduction for a predetermined plurality of courses, and (c) reduction to a speed lower than either (a) or (b), and, after each reduction, a return to the speed set by the manual control, wherein the automatic control means is adapted to effect a gradual reduction from and gradual return to the speed set by the manual control, and comprises a worm-driven member movable to and fro to effect said gradual reduction and increase; a pair of simultaneously rotatable worms for coupling alternatively to the worm-driven member to drive it in one direction or the other according to which worm is coupled to it; and coupling means controllable by a patterning device for effecting said alternative coupling.

6. A combination according to claim 4, incorporating an automatically-operable stop device for stopping the machine, comprising a stop cam rotatable with the worms, a member movable under the control thereof to a stopping position, a catch for preventing movement of the last said member, and means controllable by a patterning device for releasing the last said catch.

7. Knitting machine speed-regulating apparatus comprising a member movable in one direction to effect a speed reduction and in the reverse direction to restore the speed, a rotatable cam for displacing said member through a predetermined amplitude to effect the speed reduction and restoration, means controllable by a patterning device for determining operative periods of the cam, a worm-driven member movable to and fro to displace the first said member independently of the cam, two worms rotat-

able simultaneously with the cam for alternative coupling to the worm-driven member to shift it in one direction or the other according to which worm it is coupled to; one worm for shifting the worm-driven member in one direction to effect and maintain a greater speed-reducing displacement of the first said member than is producable by the cam, and another worm for shifting the worm-driven member in the other direction to result in speed restoring movement of the first said member, coupling means for effecting said alternative coupling, a stop cam rotatable with the worms, a stop member movable under the control thereof to a machine-stopping position, and a control member, movable under the control of a patterning device, for (a) effecting the aforesaid alternative coupling and (b) determining the movement of the stop member.

8. For moving a speed controlling member of a knitting machine to and fro to reduce and increase the machine speed, the reduction being proportional to the extent of movement of said member in a speed-reducing direction, an automatic control unit comprising a member movable to and fro and adapted to be coupled to the first said member to move it, a rotatable cam shaft, a cam thereon for moving the second member to a predetermined extent in the speed-reducing direction, a follower on the second member for engaging the cam, a catch, controllable by a patterning device, for retaining the second member in the extreme position to which it is moved by the cam, whereby according to the operation of the catch said second member is displaced and returned during a revolution of the cam or is held in the displaced position for a predetermined period in excess of one revolution, means, controllable by a patterning device, for shogging the follower into and out of register with the cam to render the latter operative and inoperative as required, two worms of opposite spirality in the cam shaft, a worm-driven member movable to and fro for effecting, upon move-

ment in one direction, a greater speed-reducing movement of the second member than is caused by the cam, means, controllable by a patterning device, for coupling the driven member to either of the worms to be shifted thereby in one direction or the other according to the worm to which it is coupled, and a connection between the driven member and the second said member for moving the latter in one direction or the other according to the direction in which the driven member is shifted by a worm.

9. A unit according to claim 8, having a part, movable under the control of a patterning device, for shogging the follower and for releasing the catch.

10. In a Cotton's patent or other straight bar knitting machine, speed control apparatus comprising a manually movable member affording an infinitely variable speed control by the operator, and automatic control means affording (a) an automatic speed reduction for one course for fashioning and a return to the speed originally obtaining; (b) an automatic speed reduction for a given number of courses and a return to the speed originally prevailing; (c) an automatic reduction to a particularly low speed, to permit of automatic movements, and a return to the original speed; and (d) an automatic stoppage of the machine at a predetermined point in time, wherein the automatic control means is adapted to effect a gradual reduction from and gradual return to the speed set by the manual control, and comprises a worm-driven member movable to and fro to effect said gradual reduction and increase; a pair of simultaneously rotatable worms for coupling alternatively to the worm-driven member to drive it in one direction or the other according to which worm is coupled to it; and coupling means controllable by a patterning device for effecting said alternative coupling.

GEORGE WILDERS.
JOHN EDWARD LYNAM.
